MENSTRUAL CALENDAR DEVICE

William R. Wenzel, Maspeth, N. Y., assignor of
one-third to Thomas A. Laquidara and one-
third to Joseph C. Sirkin, both of New York,
N. Y.

Application July 24, 1948, Serial No. 40,521

2 Claims. (Cl. 235—86)

1

The present invention relates to a novel menstrual calendar device, adapted to indicate the occurrence of the commencement of menstruation during a future period of time, upon simple adjustment or setting, determined by a known date in the cycle.

An object of this invention is to provide a novel and improved device of the character mentioned, which never calls upon the user to make any computation. With the knowledge of but a single date when a menstrual period had commenced, a setting is made in simple fashion. The device indicates future dates, readable at a glance.

Another object hereof, is to provide an indicating device of the type set forth, of novel and improved construction, which shows not only all the dates in the cycle for the calendar year, but requires no computation to be made to determine the setting of the device for the following year. It is deemed most practical that a single setting shall show the days of the ensuing year when commencement of menstruation begins.

A further object of this invention is to provide a device of the nature described, of novel and improved construction, which accounts for leap years, requires no computation for the setting, or more than one setting for any calendar year.

Another object hereof is to provide an indicating device of the kind mentioned, of novel and improved construction, and new mode of operation and functional relationship between its components, which is simple in construction, cheap to manufacture in various forms which may be very compact and small in size convenient to be carried in a hand bag, easy to use and efficient in carrying out the purposes for which it is designed, and adaptable for other purposes.

Other objects and advantages will become apparent as this disclosure proceeds.

In the accompanying drawings forming part of this specification, similar characters of reference indicate corresponding parts in all the views.

Fig. 1 is a perspective view showing an embodiment of this invention.

Fig. 2 is a section taken at lines 2—2 in Fig. 1.

Fig. 3 is a perspective view of a modified form of a device, embodying the teachings of this invention. It consists of a pair of circular discs, pivotally secured at center. Other features of construction, will be hereinafter fully set forth.

Fig. 4 shows a surface of one of said discs.

Fig. 5 is a perspective view of another embodiment of this invention.

In the drawings, referring to Figs. 1 and 2, the embodiment shown comprises a casing indicated

2

generally by the numeral 15, which may be made of plastic, metal or other suitable material, in which are journaled two spaced rollers 16 and 17, in parallel relation, frictionally engaged by an endless belt 18 carried on such rollers. The shaft of one of said rollers extends exterior the casing and carries a knob 19 for turning same to move the said belt. The belt may be of any suitable sheet material, as paper, cellophane, fabric or the like, having printed or otherwise shown thereon, thirteen aligned rows of numerals; all such rows being along the belt on the upper surface thereof, and adjacent each other successively, across the width of said surface. The casing 15 has an opening or window 20, which extends across the width of the belt 18, and is so shaped or formed that it exposes to view, a line of numbers across the rows on the belt, as well as the numbers in the first two rows only, in the line immediately following.

On the casing 15, at each row position, is shown the name of a month; the first being preferably a designation for January, the second for February, and so on for the successive months of the year. The thirteenth designation is for January of the following year.

Normally, the occurrence of menstruation is every twenty-eight days. The numbers therefore, in the "January" row at the left in Fig. 1, are the series from 1 through 28, in succession. However, in the space with the numeral "1" also appears the numeral "29"; in the space with the numeral "2" also appears the numeral "30," and in the space with the numeral "3" also appears the numeral "31." The numbers in successive months from left to right, are twenty-eight days' difference, and at every appearance of "1" there is also "29"; at every appearance of "2" there is also "30" and at every appearance of the numeral "3" on the belt 18, there is also the numeral "31." Except that in the "January" row at the right in Fig. 1, the numerals "1," "2" and "3" appear alone, because the function of this row of figures is only to indicate the date for setting the belt for the coming year after the first twelve months shown.

In use, suppose a lady acquired this device and her last menstrual period commenced say, June 24. She will turn knob 19, until the numeral 24 will appear in window 20 under the month marking "June" on the casing 15. She will therefore see at a glance that subsequent menstrual periods if normal, will occur on July 22, August 19, September 16, October 14, and so on, and that for January of next year, she shall set the belt 18

so that reading under "January" at the left, shall be the numeral "6" as is indicated now under the reading "January" at the right. If for instance her menses in October shall occur a day early, then she shall set the belt to read "13" under October, to make correction for subsequent readings.

For years, not leap years, the readings for a whole year are across a single straight line. For leap years, the readings from March through December and the following January, are in a single straight line, but the readings for the months of January and February immediately preceding said month of March, are the figures on the belt 18, which are in the very next line 15 whose "January" is one number higher than the "January" in the "March" to "December" line.

In Fig. 1, considering the year not a leap year, and that the menstrual period for January is the 7th, then subsequent menstrual periods are 20 shown in the straight line across the belt 18, to be February 4, March 4, April 1, April 29, May 27, June 24, etc. If the year is a leap year, then the belt is set so that the reading for "January" at the right in Fig. 1, say it is the 8th of January, is the figure "8" at the lower edge of the enlarged portion of window 20, as shown in Fig. 1. Here, the readings for a leap year, would be January 8, February 5, March 4, April the 1 and the 29, May 27, etc., as illustrated. Depending whether 25 the year is leap year or not, would determine the setting to be made for "January" at the left, of the belt 18.

Although mention is here made of the "twenty-eight day cycle," it is evident that the numerals on the belt 18, may be for other intervals, for the purpose mentioned, or as other uses of this device may dictate.

This device may take other forms of structure, as for instance the embodiment shown in Figs. 3 and 4, where a pair of thin discs 21 and 22, in superimposed relation are revolvably joined by a rivet or eyelet 28 at their centers. One disc 22, on its "hidden" face has printed thereon in concentric lanes, the numbers appearing in the respective longitudinal rows along the belt, so that the lines of numbers which appeared across belt 18, now are positioned along radial lines on disc 22. The other disc 21, is provided with a cut-out, or window 23, along a radius and of a shape and for the purpose which are akin those of window 20. Of importance, of course, are the edges of the opening 23, indicated by the numerals 23' and 23''. Another embodiment is in the form as shown in Fig. 5, where the rows of figures appear adjacent one another along the surface of a ruler 26 or the like, over and along which ruler is mounted for sliding, the slide member 24, hav-

ing a window or cut-out 25, similar to those herebefore described. The manner of operation of either of these modified embodiments, in view of explanation already given, is evident, and 5 needs no further details.

As matter of nomenclature, rows of numerals may better be termed as lanes of numerals, because in several instances in each row, two numerals appear in a single line.

This invention is capable of numerous forms and various applications without departing from the essential features herein disclosed. It is therefore intended and desired that the particular descriptions herein shall be deemed illustrative and not restrictive and that the patent shall cover all patentable novelty herein set forth; reference being had to the following claims rather than to the specific embodiments herein to indicate the scope of this invention.

I claim:

1. In a device of the character described, a member having a surface presenting twelve lanes of numerals in parallel side-to-side relation and a second member moveably associated with the first member, having a surface positioned adjacent the said surface of the first member and presenting edges constantly across said lanes along numerals in one line of two of said lanes and along the numerals in the line immediately adjacent said first line, of numerals in the remaining lanes; all the numerals along said second line in all the lanes and the numerals of said two lanes in the first line, being exposed to view at all relative positions of said members; the numerals in one of said two lanes being of all the days of a calendar month and the numerals of all of the lanes along the respective lines of numerals across the first member, bearing a relation of a predetermined time interval; the surface of the second member bearing indicia at each of the lanes indicating the months of the calendar year with the indicia for January at one of said two lanes.

45 2. A device as defined in claim 1, wherein said two lanes are the first two with the first lane at the indicia for January and the following lanes at the indicia indicating the remaining months of the year, in sequence.

WILLIAM R. WENZEL.
